Patented Sept. 1, 1914.

UNITED STATES PATENT OFFICE.

FRANK W. MILLER, OF CHICAGO, ILLINOIS, ASSIGNOR OF ONE-HALF TO CLARENCE D. BAUERS, OF CHICAGO, ILLINOIS.

BOILER WASHING AND FILLING SYSTEM.

1,109,351.

Specification of Letters Patent.

Patented Sept. 1, 1914.

Application filed October 30, 1911. Serial No. 657,492.

To all whom it may concern:

Be it known that I, FRANK W. MILLER, a citizen of the United States, residing at Chicago, in the county of Cook and State of Illinois, have invented certain new and useful Improvements in Boiler Washing and Filling Systems, of which the following is a specification.

This invention relates to boiler washing and filling systems adapted for utilizing the blow-off contents of locomotive boilers for heating clean fresh water for refilling purposes and has been devised with certain objects and advantages in view, aiming to increase the efficiency of systems of this character and to decrease the attention and manual manipulation required in operating the same.

One of the objects of the present system is to provide water at a suitable temperature for washout purposes so that no tempering need be done by the washers-out at the drops and with this end in view the invention comprises automatic devices which maintain the temperature of the washout water in a reservoir between certain predetermined limits.

Another object of the invention is the provision of mechanism for automatically opening the bottom of the scale pocket at predetermined intervals to permit the discharge of its contents. The pocket is thereby cleaned and freed from scale which under ordinary conditions accumulates and incrustates in the pocket, eventually filling the pocket with solid matter and destroying its usefulness.

Another object of the invention is the provision in a system of this character of a feed water heater in which the water to be used for refilling locomotive boilers and also to be supplied to the power boilers is heated to a predetermined temperature by the exhaust steam from the power boilers and, if required, by the admission of live steam.

Still another object is to condense the surplus blow-off steam which rises from the filling water heater and the washout reservoir and to convey this water of condensation to the feed water heater so that this water of condensation and also the heat units of the surplus steam are conserved.

Other objects and advantages of this invention will be apparent to those skilled in the art as the invention becomes better un-

derstood by reference to the following description when considered in connection with the accompanying drawings the single figure of which illustrates diagrammatically one embodiment of the invention.

Referring to the drawings, 5 designates a filling water heater of well known construction which comprises inner heads 6 (one only of which is shown) spaced from the ends of the heater, the compartments outside these heads being connected by pipes or flues 7 through which the blow-off steam and water blown off from a locomotive or other boiler through the blow-off line 8 pass from one end of the heater to the other and back again before being discharged from the heater through the discharge pipe 9. A branch connection 11 is located in the blow-off line, the upper branch being connected with a pipe 12 which conveys the exhaust steam from the pumps to the connection where it is mingled with the blow-off contents of the boiler and carried through the heater 5 with said contents. A check valve 13 is interposed in the pipe 12 to prevent the blow-off steam from passing back to the pumps in case the pressure in the blow-off line exceeds that in the exhaust pipe from the pumps. The lower branch of the connection 11 is connected by a pipe 14 with a scale pocket 15 of usual construction, said scale pocket being adapted to receive the scale and other solid matter blown off from the boiler with the steam and water. A hand valve 16 is located in the blow-off line 8 between the connection 11 and the heater 5, so that all the contents of a boiler may be blown off through the scale pocket 15 directly to the sewer, if desired, without passing through the heater 5. This valve may be also temporarily closed to cause the discharge of the blow-off products through the scale pocket for the purpose of effectively cleaning the same.

Since the scale, sediment and other solid matter blown off from the boilers accumulates quite rapidly in the scale pocket it is necessary to clean the pocket at frequent intervals and heretofore this cleaning has been done by hand, usually by manually opening the lower end of the scale pocket permitting the contents to be discharged therefrom. In usual practice, however, the engineer or the operator in charge of the plant often forgets to clean the scale pocket.

and as a result the pocket becomes full to overflowing so that its usefulness is entirely destroyed and, furthermore, the scale and sediment become hardened and incrusted upon the walls of the pocket so that it is only with great difficulty that the solid matter is all cleaned out. In my present invention I aim to obviate any possibility of excessive accumulation of scale and other solid matter in the scale pocket by automatically opening the lower end of the scale pocket at predetermined intervals so that all of the contents thereof will be discharged directly to the sewer, the discharge being facilitated by the blow-off steam and water under pressure in the blow-off line and in the pocket. One form of mechanism for accomplishing this result is illustrated in the drawings and comprises as shown a valve 17 located in the pipe 18 leading from the scale pocket to the sewer pipe 19, this valve being normally held in closed position by a spring 21 connected at one end with any suitable stationary pin or support and at its other end with an armature 22 connected by a link 23 with an arm or lever 24 mounted on the turning valve stem of the valve 17. An electro-magnet 25 is mounted adjacent the armature so that when said magnet is energized the armature will be attracted thereby actuating the lever 24 and opening the valve 17 to permit the discharge of the scale pocket contents. The electro-magnet is connected by suitable wires 26 with a clock controlled circuit breaker 27 of any preferred construction, the circuit breaker being adapted at predetermined intervals to close the circuit and energize the electro-magnet. The circuit is automatically broken after being completed for a predetermined period sufficient to permit the thorough cleaning of the scale pocket, whereupon the valve 17 is automatically closed and remains in closed position until the next energization of the magnet. It will be obvious that by means of this construction the scale pocket is intermittently and automatically cleaned out without requiring the attention of the engineer and 50 without possibility of the cleaning operation being delayed.

A reservoir 26 adapted to serve as a storage and heating tank for water to be used for washing out locomotive boilers is located at a lower level than the refilling water heater 5 so that the blow-off contents delivered from the heater through the pipe 9 will flow by gravity to the reservoir. A predetermined water level is maintained in the reservoir by a branch supply pipe 27 connected through the main 28 with the city water pressure or any other suitable source of water supply, the delivery of water through said branch to the reservoir 60 being controlled by a float valve 29 con-

nected with a float 31 which operates in a float chamber 32 connected with but located outside the reservoir. A coil 33 is arranged in the reservoir 26, the upper end of the coil being connected with the pipe 9 so that the blow-off contents discharged from heater 5 may be circulated through this coil to heat the water contained in the reservoir. A check valve 34 is interposed in the coil to prevent reverse flow and check valves 35 located in lateral branches 36 of the coil are provided to permit a portion of the blow-off products circulating through the coil to be discharged directly into the reservoir and mingled with the water therein. In order to maintain a predetermined level of water in the coil an upright pipe 37 is connected with the end of the coil, the upper end of this pipe communicating through a pipe 38 with a discharge pipe 39 leading directly to the sewer pipe 19. The pipe 38 also serves as an overflow pipe for the reservoir 26, the inner end of this pipe being upturned as indicated at 41 so that when the water in the reservoir reaches the upper end of this pipe it will overflow through the pipes 38 and 29 to the sewer. A check valve 38' prevents reverse flow through the pipe 38. In order that the coil 33 may be cleaned out at any time a pipe 42 connects the lower end of the coil with the sewer pipe 19, a hand valve 43 being interposed in the pipe 42 to normally close this pipe so that the contents of the coil will be normally discharged through the pipe 38.

The water contained in the reservoir 26 is intended to be used for washing out locomotive boilers after they have been blown-off and, since the washers-out can not handle the washout nozzles if the water is too hot and since the baffle plates will be injured if the water is too cold, it is necessary that the washout water be delivered to the washout nozzles at a predetermined temperature which is in actual practice as hot as the washers-out can handle. Prior to my present invention it has been customary to temper the washout water either at the drops in the roundhouse or in the discharge pipe leading from the washout pump. In either case, however, the temperature of the water fluctuated more or less by reason of the fact that the temperature of the water in the washout reservoir varied, depending upon the number of engines which had been or were being blown off at the time of the washing out operation. My present invention aims to eliminate the tempering of the washout water outside the washout reservoir and, with this end in view, I have provided certain regulating devices which maintain the temperature of the water in the reservoir between predetermined limits. For the purpose of preventing the water in the reservoir from falling below a predetermined tem-

perature a pipe 44 connected with any suitable source of live steam supply enters the reservoir and is provided with branches 45 having perforations through which the steam is permitted to escape into the water contained in the reservoir. A thermostat valve 46 is disposed in the pipe 44 and is controlled from a thermostat 47 projecting into the reservoir. When water in the reservoir falls below a predetermined temperature the valve 46 is automatically opened to admit sufficient live steam to raise the water to a predetermined temperature, whereupon the valve 46 is closed. The washout water in the reservoir is primarily heated, however, by the blow-off products delivered to the coil 33 and, if the blow-off products are permitted to be continually introduced into the coil, it will be obvious that the temperature of the water in the reservoir may become too hot for washout purposes unless it is being constantly used and replaced by cold water from the pipe 27. In order to divert the blow-off contents from the coil when the washout water is hot enough I have provided a thermostatically controlled valve 48 located in the branch pipe 49 connecting the discharge pipe 9 with the discharge pipe 39. A thermostat 50 arranged inside the reservoir 26 controls the valve 48 and, when the water in the reservoir rises to a predetermined temperature, the valve 48 is opened thereby permitting the blow-off contents conveyed from the heater 5 by the pipe 9 to be discharged through the pipes 49 and 39 to the sewer. When the temperature of the water in the reservoir again lowers the valve 48 is automatically closed and the blow-off products are again delivered to the coil 33 to heat the water to a suitable temperature for washout purposes. The washout water is drawn from the reservoir by a pump 51 through an intake pipe 52 and is discharged through the delivery pipe 53 into the washout line 54 by which it is conveyed to the drops in the roundhouse.

In practice it is customary to locate the washout and refilling plants adjacent the machine shops and the power plants therefor, and the exhaust steam from the various engines and pumps of the power plant is customarily conveyed to a feed water heater for heating water to be supplied to the power boilers. My present invention contemplates heating the water to be supplied to the power boilers not only by the exhaust steam from the power plant but also by the blow-off contents of the locomotive boiler and I have, therefore, in my present system combined a feed water heater 55 with the refilling water heater and washout water reservoir previously described so that a most efficient and economical system is produced. Any preferred type of feed water heater may be employed in this system but I have

shown, for purposes of illustration, a heater having a dome or upper chamber 56 equipped with plates 57 arranged in staggered relation over which water supplied through the branch 58 from the main 28 flows and is heated by mingling with the exhaust steam from the power plant conveyed to the feed water heater by the pipe 59. A predetermined level of water is maintained in the feed water heater by a float 60 located in the float chamber 62 connecting with the interior of the heater, which float, by suitable connections, controls a float valve 63 disposed in the water supply branch 58. Water in the feed water heater is maintained at a predetermined temperature by the admission of live steam through a pipe 61 equipped with a thermostatically controlled valve 70 which is governed by a thermostat 63 projecting into the interior of the heater. The water which has been heated in the feed water heater is withdrawn therefrom by the pump 64 through an intake pipe 65 and is delivered through a pipe 66 to the refilling water heater around the tubes 7. From the refilling heater wherein the water is additionally heated by the blow-off products passing through the tubes 7 the water is conveyed to the drops in the roundhouse for refilling purposes through the refilling line 67 or to the power boilers in the power plant through the pipe 68. Suitable valves 69 and 71 are located in the pipes 67 and 68, respectively, so that the flow of water in both directions can be regulated or controlled at will. In order that the water to be used for refilling the locomotives and for supplying the power boilers may be heated to a uniform temperature by the blow-off products passing through the heater 5 I have provided a return or circulating pipe 72 connecting the boiler line 68 with the feed water heater, so that circulation will be continually maintained by the pump 64 through the pipes 65, 66, heater 5, pipe 68 and pipe 72. A hand valve 73 is disposed in the pipe 72 so that the amount of water permitted to circulate can be regulated.

In order to utilize the blow-off steam which is not condensed in the heater 5 and all steam not condensed in the reservoir 26, I have provided a plurality of condensers 74 and 75, respectively. The condenser 74 communicates with the interior of the heater 5 beneath the baffle plate 76 through a pipe 77 and a branch pipe 78 leading from the pipe 77 communicates with the interior of the reservoir 26. It will be evident that any surplus steam in the heater 5 beneath the baffle plate 76 and in the reservoir 26 will rise to the condenser 74 wherein it will be condensed and returned through the pipe line 78 to the feed water heater. The condenser 75 is connected with the heater 5 at the opposite end of the heater from the pipe 77 by

means of a pipe 79. A blow-off valve 81 is interposed in the pipe 79 which opens only when the pressure in the heater rises above a predetermined amount. The water of condensation delivered by the pipe 78 from the condensers 74 and 75 is mingled in the feed water heater with the water contained therein and is subsequently returned to the locomotive boilers or to the power boilers from the heater 5. It will thus be obvious that all the surplus steam in the heater 5 and in the reservoir 26 is utilized, that portion which is not condensed in heating the refilling water in the heater 5 or the washout water in the reservoir 26 being condensed by the condensers 74 and 75 and returned to the feed water heater.

In order that the pressure in the feed water heater may not rise above a safety point I have provided a blow-off pipe 82 provided with a back pressure valve 83 through which excessive pressure is permitted to escape to the atmosphere. Pipes 84 and 85 equipped with suitable hand valves connect the end compartments of the heater 5 with the discharge pipe 39 through a pipe line 86. These pipes are provided for cleaning out the end compartments of the heater, when desired. A pipe 87 equipped with a hand valve connects the compartment around the tubes 7 with the pipe 86 so that this compartment may also be cleaned out when occasion requires and branch pipes 88 and 89 likewise equipped with hand valves are connected with the bottom of the reservoir 26 through which the contents of said reservoir may be discharged to the sewer and the reservoir may be cleaned when desirable.

40. The blow-off, washout and refilling lines are arranged in the roundhouse in the usual manner and are provided with suitable drops preferably disposed between the engine pits and equipped with valves and connections so that they can be readily connected to the locomotive boilers positioned over the pits. I have not deemed it necessary in the present instance to illustrate the pipe lines in the roundhouse as the arrangement and connections may follow any well known or preferred design.

It is believed that the invention, its mode of operation and many of its attendant advantages will be understood from the foregoing without further description and it will be obvious that various changes in the construction and arrangement of the various parts may be resorted to without departing from the spirit of the invention or sacrificing any of the material advantages thereof.

60. I claim:

1. In a boiler washing and filling system, the combination of a reservoir, means for maintaining a predetermined level of water in said reservoir, means for conducting the

blow-off steam and water of a boiler to said reservoir, and thermostatically controlled means for preventing said blow-off steam and water from entering said reservoir when the water in the reservoir is above a predetermined temperature. 70

2. In a boiler washing and filling system, the combination of a reservoir, a coil arranged in said reservoir, means whereby said coil may be connected with a locomotive boiler to permit the blow-off steam and water of said boiler to be delivered to the coil, means for supplying water to said reservoir, and means for diverting the blow-off steam and water of a boiler from said coil when the water in the reservoir reaches a predetermined temperature. 80

3: In a boiler washing and filling system, the combination of a filling water heater, a blow-off line connected therewith to deliver blow-off steam and water to said heater, a reservoir, a pipe connecting said filling water heater with the reservoir for delivering said blow-off steam and water from the heater to the reservoir, means for supplying water to said reservoir, and a thermostatically controlled valve for permitting the blow-off contents of a boiler delivered from said filling water heater to be discharged outside said reservoir when the water in the reservoir reaches a predetermined temperature. 85 90 95

4. In a boiler washing and filling system, the combination of a reservoir adapted to contain water for washout purposes, a coil arranged in said reservoir to convey the blow-off contents of a boiler therethrough, means for permitting a portion of said blow-off contents to be discharged into the reservoir, means for maintaining a predetermined water level in said reservoir, and means for preventing said blow-off contents from entering said coil when the water in the reservoir reaches a predetermined temperature. 100 105 110

5. In a boiler washing and filling system, the combination of a blow-off line, a scale pocket connected therewith, a filling water heater adapted to receive blow-off steam and water from said blow-off line, a reservoir, means for conducting blow-off steam and water from said heater through said reservoir, means for supplying water to said reservoir, means controlled by the temperature of the water in said reservoir for diverting the blow-off steam and water from said heater directly to a sewer, means normally closing the bottom of said scale pocket, and automatically and intermittently actuated means for opening the bottom of said scale pocket at predetermined intervals. 115 120 125

6. In a boiler washing and filling system, the combination of a filling water heater, a blow-off line connected therewith, a scale pocket communicating with said blow-off 130

line, means for automatically and intermittently opening the bottom of said scale pocket at predetermined intervals, a washing water reservoir, connections between said reservoir and said filling water heater for conducting the blow-off steam and water delivered to said heater by the blow-off line from said heater to the reservoir, and means for diverting said blow-off steam and water from the reservoir when the washing water in the reservoir reaches a predetermined temperature.

7. In a boiler washing and filling system, the combination of a filling water heater, a washout reservoir, a blow-off line connected with said heater, a scale pocket communicating with said blow off line to receive scale and sludge from the blow off products, a valve normally closing the lower end of said scale pocket, automatic means for intermittently opening said valve at predetermined intervals and retaining said valve in open position for a predetermined period, and means for automatically closing said valve at the end of each of said periods.

8. A boiler washing and filling system comprising a filling water heater, a blow-off line connected therewith, a feed water heater, means for maintaining a predetermined level of water in said feed water heater, means for condensing the steam rising uncondensed from the filling water heater, a pipe for conveying the water of condensation to the feed water heater, means for conveying water from said feed water heater to the filling water heater, and a refilling line for conducting said water at refilling water to a locomotive boiler.

9. In a boiler washing and filling system, the combination of a filling water heater, a condenser connected therewith for condensing the steam rising from said heater, a feed water heater, a pipe for conveying the water of condensation from said condenser to said feed water heater, means for maintaining a predetermined level of water in said feed water heater, means for admitting live steam to heat said water when the temperature falls below a predetermined point, means for conducting water from said feed water heater to said filling water heater, a blow-off line for conveying the blow-off products of a boiler to said filling water heater to heat the water contained therein, and a refilling line for conveying said heated water to a boiler for refilling purposes.

10. In a boiler washing and filling system, the combination of a refilling water heater, a washout reservoir, a feed water heater, means for conveying the heat of the blow-off contents of a boiler to the water in the refilling heater and the water in the washout reservoir, means for condensing the steam

rising from said filling water heater and from said washout reservoir, a pipe for conducting the water of condensation to the feed water heater, means for conducting water from the feed water heater through the filling water heater to a boiler for refilling purposes, and means for conducting water from said washout reservoir to a boiler for washout purposes.

11. In a boiler washing and filling system, the combination of a washout reservoir, a feed water heater, means for maintaining a predetermined water level in said reservoir and heater, means for heating the water in the reservoir from the blow-off contents of a boiler, means for condensing and delivering to the feed water heater the steam rising uncondensed from said reservoir, means for automatically heating the water in said reservoir and in said feed water heater to predetermined temperatures, means for conveying water from said feed water heater to a boiler for refilling purposes, and means for conveying water from said reservoir to a boiler for washout purposes.

12. In a boiler washing and filling system, the combination of a filling water heater, means for delivering the blow-off contents of a boiler to said heater, a feed water heater, means for heating the water in said feed water heater, means for conducting water from said feed water heater to the filling water heater, means for conveying heat of the blow-off contents of a boiler to the water in said filling water heater, and a return pipe connecting said filling water heater and feed water heater to maintain a circulation through said heaters.

13. In a boiler washing and filling system, the combination of a filling water heater, a reservoir for washout water, a blow-off line, a scale pocket connected therewith, means for automatically opening the scale pocket at predetermined intervals to permit the same to be cleaned, a coil arranged in said reservoir, connections between said coil and the blow-off line whereby the blow-off contents of a boiler may be conveyed to said coil, means for automatically regulating the admission of said blow-off contents to the coil, a feed water heater, means for condensing the steam rising from said reservoir and said filling water heater, means for conveying the water of condensation to said feed water heater, means for delivering water from said feed water heater to the filling water heater, a refilling line connected with said filling water heater, and a washout line connected with said reservoir.
